(57) **CLAIM**

The ornamental design for a steam generating base for laundry iron, as shown.

DESCRIPTION

FIG. 1 is a top, front and side perspective view of a steam generating base for laundry iron, showing my new design;

FIG. 2 is a front elevational view thereof;

FIG. 3 is a side elevational view thereof from the left of FIG. 2;

FIG. 4 is a side elevational view thereof from the right of FIG. 2;

FIG. 5 is a rear elevational view;

FIG. 6 is a top plan view thereof; and,

FIG. 7 is bottom plan view thereof.
